CARPET SWEEPER CASE

Fred W. Pullen, Grand Rapids, Mich., assignor to
 Bissell Carpet Sweeper Company, Grand
 Rapids, Mich.

Application June 11, 1932. Serial No. 616,643

7 Claims. (Cl. 15—41)

The objects of this invention are:

First, to provide a simple and economical construction of carpet sweeper case especially adapted to the use of a sheet metal shell or a similar sheet construction.

Second, to provide such a structure which is easily assembled.

Third, to provide such a structure in which the minimum number of nails or screws are used.

Objects pertaining to details of my invention will appear from the description to follow. The invention is defined in the claims. A structure which is a preferred embodiment of my invention is illustrated in the accompanying drawing, in which:

Fig. 1 is an end elevational view of a carpet sweeper embodying my invention.

Fig. 2 is a detail view of the top of the shell showing certain parts in dotted lines.

Fig. 3 is a section taken on line 3—3 of Fig. 2.

Fig. 4 is a perspective view showing the parts in disassembled relation.

Fig. 5 is a perspective view showing the parts of a modification of my invention in disassembled relation.

Fig. 6 is a detail of the top of the shell used in the modification showing some of the parts in dotted lines.

Fig. 7 is a sectional view taken on line 7—7 of Fig. 6.

The parts will be identified by their numerals of reference.

My improved case 1 comprises a sheet metal shell 2 with the sides downturned and the case ends 3 which are here shown as of wood but may be of any desired material.

The sweeper has the usual floor wheels 4, side bars 5 having a groove 6 therein in which the side edge of the shell 2 is inserted. Outer metallic frame bars 7 extend around the side bars 5 and buffer construction 8 with cord 9 is provided therearound.

The case ends 3 are held between the side bars 5, nails 10 passing through the frame bars 7 pass through the side bars 5 and into the edges of the case ends 3 to hold them in position. The case ends 3 are slotted as at 11 for admission of the brush 12 as is customary.

In the sweeper shown in Fig. 1, a dump lever 13 is provided having an inner arm 14 engaging spring pan opening means 15 which is not here fully illustrated but which is set forth and described in my copending application for Letters Patent, Serial No. 585,423, filed January 8, 1932.

Depending from the shell 2 are portions 16 having thereon inturned flanges 17 to form L-shaped inturned end flanges adapted to engage slots 18 in the case end 3 in the structure illustrated in Figs. 1 to 4. The flange 16 extends down the sloping sides of the shell 2 as at 19 but the flange 17 as here illustrated extends only across the top of the shell 2, although if desired it could extend down onto the extensions 19.

A plate 20 is provided adapted to overlie the depending portion 16. The plate is provided with holes 21 to receive screws 22 to fasten the plate to the case end 3.

The plate shown in Figs. 1 to 4 has a socket 23 therein to receive the nib of a bail 24 and has raised stops 25 to hold the bail in vertical position when the sweeper is not in use.

It will be seen that by this construction the flange 17 engages the slot 18 and the plate 20 engaging the depending portion 16 and being fastened to the case end 3 holds the shell 2 and case end 3 firmly together.

In the modification shown in Figs. 5 to 7, there is on sheet metal shell 102 a depending portion 116 having a flange 117 adapted to engage a slot 118 in the case end 103 and there is an ear 199 depending from the portion 116 and overlying the case end 103. A plate 120 provided with holes 121 fits over ear 199 and screws 122 pass through holes 121 and through holes 124 in ear 199 to engage the case end 103 and bind the shell 102 and the case end 103 together. Stops 125 are raised on the plate 120 to hold the bail 126 in upright position when the sweeper is not in use, and in the case end 103 is a socket 123 for the nib of the bail 24.

In using a metal shell 2 or 102 and the spring pan opening means 15, it is necessary to provide a stop so that the means 15 will not disfigure the shell 2 or 102 by continually hitting thereagainst.

In the construction shown, I provide a strip or block 26 to lie along the shell 2 or 102 at the point where means 15 would engage the shell. This block is of wood but may be of any desired material and is held in place by means of a recess above the case end 3 or 103 formed by pressing up a panel 27 in the shell 2 or 102. The block 26 is held in the recess shown as at 28 frictionally when the case end and the shell are fastened together. If desired, a strip can be placed across the top of the sweeper case 2 or 102 or the case end 3 or 103 may be recessed to hold the block 26. The illustrated construction is desirable from a manufacturing point of view.

It will be seen that the case structures illustrated are very staunch and that the sheet metal with its depending portion and flange firmly clamps the case end 3 or 103 and the plate 20 or 120 holds the structure firmly together producing a very economical and simple construction with the use of only two screws or other fastening means at the top thereof.

The structure as described is clearly capable 10 of considerable modification without departing from the invention. Sheet metal is specified and is especially adapted to this use but other sheet material is available.

Having thus described my invention, what I 15 claim as new and desire to secure by Letters Patent, is:

1. In a carpet sweeper case, the combination 20 of a substantially rectangular shell body with sloping sides having depending inturned end flanges, case ends conformed to said shell each having a groove therein to receive one of said flanges, a plate at each end overlying a portion of the flange and fastened to the case end whereby the shell and case end are firmly bound together, and a stop retained between said shell 25 and the top of each of said case ends and extending inwardly of said case.

2. In a carpet sweeper case, the combination 30 of a substantially rectangular shell body with sloping sides having depending inturned end flanges, case ends conformed to said shell each having a groove therein to receive one of said flanges, and a bail socket plate at each end overlying a portion of the flange and fastened to the 35 case end whereby the shell and case end are firmly bound together.

3. In a carpet sweeper case, the combination 40 of a substantially rectangular shell body with sloping sides having depending inturned end flanges and having depending ears, case ends conformed to said shell, each having a groove therein to receive one of said flanges, and a plate at each end overlying said ear, and means fastening said plate and said ear to the case end 45

whereby said shell and case ends are firmly bound together.

4. In a carpet sweeper case, the combination 80 of a substantially rectangular shell body with sloping sides having depending inturned end flanges and having depending ears, case ends conformed to said shell, each having a groove therein to receive one of said flanges, and a plate at each end overlying said ear, means fastening said plate and said ear to said case end whereby 85 said shell and case ends are firmly bound together, and a stop retained between said shell and the top of each of said case ends and above said ears and extending inwardly of said case.

5. In a carpet sweeper case, the combination 90 of a substantially rectangular shell body with sloping sides having depending inturned end flanges, case ends conformed to said shell each having a groove therein to receive one of said flanges, side bars having grooves to retain the 95 sides of said shell, means for fastening said side bars to said case ends, and means at each end overlying a portion of said flange and fastened to the case end, whereby the shell and case end are firmly bound together. 100

6. In a carpet sweeper case, the combination 105 of a substantially rectangular shell body with sloping sides having depending inturned end flanges, case ends conformed to said shell each having a groove therein to receive one of said flanges, and means at each end overlying a portion of said flange and fastened to the case end whereby the shell and case end are firmly bound together. 110

7. In a carpet sweeper case, the combination 115 of a substantially rectangular shell body with sloping sides having depending inturned end flanges, case ends conformed to said shell each having a groove therein to receive one of said flanges, and fastening means at each end fastened to the case end and extending from said flange whereby the shell and case end are firmly bound together. 117
